US0D1087719S

(12) **United States Design Patent** (10) **Patent No.:** **US D1,087,719 S**
(45) **Date of Patent:** **** Aug. 12, 2025**

(54) **CUTTING TOOL**

(71) Applicant: **Robert Bosch GmbH**, Stuttgart (DE)

(72) Inventors: **Nicholas Garcia**, Chicago, IL (US);
Ross Brinkman, Chicago, IL (US);
Richard Monteverde, Chicago, IL (US);
Mitch Burdick, Des Plaines, IL (US);
Ramon Tam, Buffalo Grove, IL (US)

(73) Assignees: **Robert Bosch Power Tools GmbH**, Stuttgart (DE); **Robert Bosch GmbH**, Stuttgart (DE)

(**) Term: **15 Years**

(21) Appl. No.: **29/894,450**

(22) Filed: **Jun. 9, 2023**

(51) LOC (15) Cl. **08-03**

(57) **CLAIM**

The ornamental design for a cutting tool as shown and described.

DESCRIPTION

FIG. 1 is a first perspective view of a cutting tool showing our new design;

FIG. 2 is a second perspective view of the cutting tool of FIG. 1;

FIG. 3 is a right side elevational view of the cutting tool of FIG. 1;

FIG. 4 is a left side elevational view of the cutting tool of FIG. 1;

FIG. 5 is a top plan view of the cutting tool of FIG. 1;

FIG. 6 is a bottom plan view of the cutting tool of FIG. 1; FIG. 7 is a front elevational view of the cutting tool of FIG. 1; and,

FIG. 8 is a rear elevational view of the cutting tool of FIG. 1.

In the drawings, broken lines represent the environment of the claimed design and form no part of the claimed design.

1 Claim, 6 Drawing Sheets
